UNITED STATES PATENT OFFICE.

DON C. MONROE, OF SHAWNEE, OKLAHOMA.

AUTOMATIC RELEASING SCREWDRIVER.

1,333,436.

Specification of Letters Patent.

Patented Mar. 9, 1920.

Application filed July 24, 1917, Serial No. 182,502. Renewed August 28, 1919. Serial No. 320,460.

To all whom it may concern:

Be it known that I, DON C. MONROE, a citizen of the United States of America, residing at Shawnee, in the county of Pottawatomie and State of Oklahoma, have invented new and useful Improvements in Automatic Releasing Screwdrivers, of which the following is a specification.

The present invention comprehends generally improvements in that class of inventions known as woodworking tools and more particularly has reference to an automatic releasing screw driver.

This invention has for its principal object to provide a device of the above character wherein the construction is novel and permits of the automatic release of a screw driver from the head of a screw at the time the screw reaches its final destination or adjustment thus preventing injury to the screw and to the tool.

As an equally important object this invention aims to provide a screw driver of the character mentioned wherein the adjusting and releasing means mounted in the main casing operates in conjunction with a guide carried by the casing for supporting a screw when being adjusted, the guide being constructed and positioned so as to assure of the actuation of the device at a predetermined time and thus release the tool from the screw.

More particularly this invention embraces the provision of a device of the above mentioned character designed to normally assure of the rotation of the screw driver shank or bit with the main stem yet also permitting of the automatic release of the screw when the latter has been fully adjusted.

It is an additional object of this invention to provide a device of the above mentioned character which is simple in construction, thoroughly reliable and efficient in its purpose and inexpensive in manufacture.

Other objects will be in part obvious and in part hereinafter set forth.

The invention accordingly consists in the features of construction, the combination of elements and the arrangement of parts which will be exemplified in the construction hereinafter described and the scope of the application of which will be indicated in the appended claims.

The invention is clearly illustrated in the accompanying drawings, in which:

Figure 1 is a vertical section of the invention partly in elevation showing the position of the parts when a screw has been fully adjusted with the screw driver bit free to rotate;

Fig. 2 is an enlarged fragmentary vertical section of the invention showing the screw driver bit in front elevation and connected to the main stem so as to rotate therewith;

Fig. 3 is an enlarged fragmentary vertical section of the invention, partly in elevation;

Fig. 4 is a perspective detail.

Similar characters of reference are employed in all the above described views to indicate the corresponding parts.

Referring now, more particularly, to the accompanying drawings, there is provided a main cylindrical casing 1 the outer end of which is open and is exteriorly screw threaded, as indicated by the numeral 2. Arranged against the outer edge of the casing is a tubular support and guide 3 for a screw 4, said support and guide being formed with an outwardly extending annular flange 5 at its upper edge while an internally threaded union 6 is employed and is designed for adjustable and removable engagement on the lower end of the casing, being also arranged about the support and guide 3 and formed with an inwardly extending annular shoulder 7 which is arranged in close relation with the outer surface of the guide and forms a support or clamp for assuring of the rigid retention of the guide against the lower edge of the casing, as indicated. The upper edge of the casing is formed with an inwardly extending annular shoulder 8 leaving an opening 9 between the edges in which is slidably and rotatably mounted a main stem 10 while a head 11 is connected to the stem and is slidably arranged within the casing, being designed for receiving a screw driver bit 12 in a manner that will hereinafter become apparent. Suitable resilient means, such as a coil spring 13, is arranged about the stem and has one of its ends bearing against a washer 14 slidable on the stem and held against the adjacent shoulder 8 of the casing while its opposite end bears against a collar 15 adjustably mounted on the stem and removably retained in rigid relation

110

therewith through the instrumentality of a set screw 16 or the like. This spring serves to normally maintain the head 11 against the inner end of the casing.

- 5 As intimated, improved means have been provided for assuring of the automatic release of the screw driver bit 12 at the time the screw 4 has been fully adjusted. In reducing this feature of the invention to practice, the head 11 is of novel construction being preferably formed with a main longitudinal bore 17 the lower portion of which is reduced as at 18 forming a shoulder 19. The upper portion of the head is also formed 15 with opposed slots 20 and is further provided with secondary bores 21 which communicate respectively with the inner ends of the slots 20 and the lower edge of the head. Suitable means, such as a transverse 20 pin 22, serves to connect the upper portion of the head to the adjacent end of the stem 10, as indicated, the respective ends of the pins 22 terminating in substantial alinement with the outer edges of the head so as not 25 to interfere with the rotation of the latter within the casing 1. A clutch disk 23 is slidably but non-rotatably mounted in the upper enlarged portion of the main bore 17 and is formed with opposed wings 24 adjacent its upper edge for slidable engagement with the slots while the lower edge of the disk is formed with a kerf or notch 25 for a purpose that will presently appear. Suitable resilient means such as a coil spring 26 30 is arranged between the disk 23 and the adjustable end of the stem for normally holding the wings at the inner ends of the slots 20. The screw driver bit has its inner reduced end 26' rotatably but non-slidably 35 mounted in the lower or restricted portion 18 of the bore. This mounting is effected preferably by forming an annular groove 27 in the reduced portion of the stem while in this groove is positioned the inner end of 40 the transversely extending screw 28 mounted in the head and having its outer edge in alinement with the outer surface of the head so as not to interfere with the movement of the head. The inner end of the bit 45 12 is reduced to form a neck or lug 29 which extends partly into the enlarged portion of the bore so as to be engaged by the notch or kerf 25 in the under surface of the clutch disk, the latter in turn being arranged in 50 close relation with the shoulder 19. Coöperating with the clutch disk is the improved actuating means therefor which in the present instance may be said to consist of a washer 30 arranged about the bit of the 55 screw driver 12 and suspended and slidably connected in the head through the instrumentality of guide rods 31 the lower ends of which are rigid with the upper surface of the washer at diametrically opposite 60 points and are slidably arranged through 65

the secondary bores 21 terminating at their upper ends in heads 32 normally seated in the bottom of the slots 20 beneath the wings 24 and of such length that the washer 30 will contact with the inner edge of the guide and support 3 simultaneously with the final adjustment of the screw 4 by the screw driver bit 12 and move the disk clutch 23 against the tension of the spring 26 so as to release the screw driver bit and allow it to lie idle in the head without acting further on the screw. 70

The mode of operation of the present invention may be reviewed as follows:—

Assuming that the parts have been assembled in the manner described and as illustrated in the drawings, subsequent to the arranging of the screw 4 within the support and guide 3 the main stem is rotated in any suitable manner and depressed against the tension of the spring 13 so as to move the screw driver into engagement with the kerf of the screw and by exerting a continual downward movement on the stem the screw 4 will be driven into an adjusted position 80. At the time the screw reaches its final destination the washer 30 will contact with the upper edge of the support and guide 3 so as to slide the rods 31 through the secondary bores 21 and inasmuch as the rods act against the wings 24 the clutch disk 23 will be raised 85 upwardly against the tension of the spring so as to release the screw driver bit 12. Inasmuch as this action temporarily releases the positive connection of the bit with the stem the bit will not act further on the screw and will thereby avoid injury to the screw and to the bit. 90

As many changes could be made in the above construction, and many apparently widely different embodiments of this invention could be made without departing from the scope thereof it is intended that all matter contained in the above description or shown in the accompanying drawings shall 105 be interpreted as illustrative and not in a limited sense. It is also to be understood that the language used in the following claims is intended to cover all the generic and specific features of the invention herein 110 described and all statements of the scope of the invention which as a matter of language might be said to fall therebetween. 115

Having thus described the invention what is claimed as new and desired to be secured by Letters Patent is:—

1. A device of the character described including a casing, a support and guide for screws detachably mounted on the lower end of the casing, a stem slidably and non-rotatably mounted in the casing, a head mounted within the casing and connected to the stem, resilient means for normally holding the head against the upper end of the casing, a resiliently and slidably mounted 125

clutch disk in the head, a screw driver bit rotatably and non-slidably mounted in the head and normally engageable by the clutch disk so as to be rotated with the stem, and 5 means slidably mounted on the head and engageable with the clutch disk so as to release the clutch disk from the bit at a predetermined period.

2. A device of the character described including a casing, a support and guide for screws detachably mounted on the lower end of the casing, a stem slidably and non-rotatably mounted in the casing, a head mounted within the casing and connected to the 10 stem, resilient means for normally holding the head against the upper end of the casing, the head being provided with a bore the lower portion of which is restricted forming an annular shoulder and being also provided with opposed slots, a clutch disk disposed in the bore, wings projecting therefrom and slidable in the slots, resilient means for normally holding the wings against the inner ends of the slots, a screw 15 driver bit rotatably and non-slidably mounted in the lower portion of the bore for removable engagement by the clutch disk, rods slidably mounted through the head and terminating at their upper ends in heads so as to be supported in the bottoms of the recesses, and a washer disposed about the screw driver bit 20 and carried by the rods and normally arranged in spaced relation to the lower edge of the head and adapted to be moved upwardly upon contacting of the upper edge of the support and guide for removing the clutch disk from engagement with the screw driver bit.

25 3. A device of the character described including a casing, a support and guide for screws mounted on the lower end thereof, a main stem slidably and non-rotatably mounted in the casing, a head connected to the stem within the casing, resilient means for normally holding the head adjacent the upper end of the casing, a screw driver bit rotatably 30 and non-slidably mounted in the head, yielding and slidably mounted clutch means in the head for normally engaging the bit so that it will rotate with the stem and means slidably mounted in the head and normally disposed beneath the lower edge thereof for engagement with the upper edge of the support and guide at a predetermined period so as to be actuated and automatically release the screw driver bit. 35

lower portion of which is restricted forming an annular shoulder and being also provided with opposed slots, a clutch disk disposed in the bore, wings projecting therefrom and 45 slidable in the slots, resilient means for normally holding the wings against the inner ends of the slots, a screw driver bit rotatably and non-slidably mounted in the lower portion of the bore for removable engagement by the clutch disk, rods slidably mounted through the head and terminating at their upper ends in heads so as to be supported in the bottoms of the recesses, and a washer disposed about the screw driver bit 50 and carried by the rods and normally arranged in spaced relation to the lower edge of the head and adapted to be moved upwardly upon contacting of the upper edge of the support and guide for removing the clutch disk from engagement with the screw driver bit.

4. A device of the character described including a casing, a support and guide for screws mounted on the lower end thereof, a main stem slidably and non-rotatably mounted in the casing, a head connected to the stem within the casing, resilient means for normally holding the head adjacent the upper end of the casing, a screw driver bit rotatably 65 and non-slidably mounted in the head, yielding and slidably mounted clutch means in the head for normally engaging the bit so that it will rotate with the stem and means slidably mounted in the head and normally disposed beneath the lower edge thereof for engagement with the upper edge of the support and guide at a predetermined period so as to be actuated and automatically release the screw driver bit. 70

In testimony whereof I affix my signature.

DON C. MONROE
